(57) **CLAIM**

The ornamental design for an optoelectronic sensor as shown and described.

DESCRIPTION

1. Optoelectronic sensor

2. Optoelectronic sensor

3. Optoelectronic sensor

3.7 : Top

The present designs show optoelectronic devices, especially laser scanners, used for industrial applications, for collision protection, for navigation in mobile applications and for area monitoring; the devices consist of the main body housing as a lower part and an upper circular cover and electrical connections to the lower part.

The broken lines are included for the purpose of illustrating portions of the optoelectronic sensor and form no part of the claimed design.
